UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT STOCK COMPANY OF FRANCE.

WATER-TIGHT BULKHEAD FOR SUBMARINES AND OTHER SUBMERSIBLE VESSELS.

Application filed June 29, 1923. Serial No. 643,557.

To all whom it may concern:

Be it known that I, EUGÈNE SCHNEIDER, a citizen of the Republic of France, resident of Paris, France, have invented new and useful Improvements in Water-Tight Bulkheads for Submarines and Other Submersible Vessels, which is fully set forth in the following specification.

The water-tight bulkheads of submarines, submersible marine vessels and other vessels designed for submersion, are required to prevent all entrance of water into certain compartments, when other parts of the vessel have been invaded by the sea. 10 These bulkheads are either flat or convex. Convex bulkheads are capable of resisting pressure acting indifferently on one side or the other of the bulkhead, and the rivets connecting these bulkheads to the pressure-resisting hull will always be under shear. On the other hand, flat bulkheads, owing to the nature of their construction, require to be strengthened by reinforcements generally constituted by girders or beams against 20 which the pressure is arranged to have a tendency to press the flat bulkhead. Owing to the great load pressing against these bulkheads which are intended to resist the same pressures as the resisting hull, the said reinforcements must have relatively considerable dimensions in the direction of the strains. The result is that behind these reinforced flat bulkheads, the space occupied by the reinforcements are not suitable for 30 accommodating ship appliances of bulky nature.

Spherical bulkheads, although they can dispense with reinforcements have likewise the drawback of constituting obstructions 40 which prevent the space behind the bulkhead from being utilized for bulky ship appliances, since the length of said space is measured by the height or depth of the arc of the spherical segment.

The present invention has for its object to provide an improved construction of strong water-tight bulkheads wherein all the above mentioned drawbacks are done away with.

According to this invention each bulkhead is combined or connected with compartments of which the bulkhead forms at least one wall element, and which compartments can serve as store rooms or tanks for

the storing of water, oil, combustible liquid, etc.

Two examples of the application and execution of the invention are illustrated in the accompanying drawings in which:

Figures 1 and 2 are respectively an elevation and a section taken along the line 2—2 of Figure 1, of an example of the application of this invention to a flat bulkhead.

Figures 3 and 4 are respectively an elevation and a section taken along the line 4—4 of Figure 3, of the application of the invention to a bulkhead having the form of a spherical segment.

In these figures, A is the stiff hull of the ship. According to this invention, the bulkhead proper B, bearing against the uprights *a* is combined with compartments D formed for example between itself and a parallel bulkhead C, which latter may have less strength than or the same strength as the bulkhead B, according as it is arranged that the pressure shall act exclusively in the direction of the arrow 1, or indifferently in the directions of either of the arrows 1 and 2.

It is to be understood that the compartments D will not occupy the whole of the surface of the bulkhead B. They will leave vacant spaces preferably at the centre for the provision of a door E. The associated bulkheads B and C may be reinforced by uprights *b* and *c* respectively, which may be strutted or stayed together both in the vertical and horizontal directions.

It is to be understood that as in the case in the illustrated example, a continuous annular compartment may be provided, or this compartment may be sub-divided by means of bulkheads or other partitions, and if desired, communications may be provided between the compartments together with suitable isolating devices.

In the example illustrated in Figures 3 and 4 a convex main bulkhead B having for instance the shape of a spherical segment, is associated or combined with the compartments D, D¹ formed on either side of the said bulkhead and limited for example by auxiliary bulkheads C, C¹ which may be flat or of any other suitable shape, and an annular bulkhead F.

Having now particularly described and

ascertained the nature of my said invention and in what manner the same is to be performed I declare that what I claim is:—

1. In a bulkhead structure, the combination of a main bulkhead, a flat auxiliary bulkhead disposed adjacent the main bulkhead and of less strength than the latter, a tubular bulkhead providing a passageway through the structure, and a closure for one end of said passageway.
2. In a bulkhead structure, the combination of a main bulkhead, reinforcing means therefor comprising compartments on one face of the bulkhead each having a wall provided by a flat auxiliary bulkhead of less strength than the main bulkhead, a tubular bulkhead inclosed by said compartments and providing a passageway through the structure, and a door for closing one end of said passageway.
3. In a bulkhead structure, the combination of a main bulkhead, a flat auxiliary bulkhead of less strength than the main bulkhead, said bulkheads being spaced apart and provided with aligned openings, an annular bulkhead secured to the main and auxiliary bulkheads adjacent said openings and providing a passageway through the structure, compartments disposed around the annular passageway between said main and auxiliary bulkheads, and a door for closing one end of said passageway.
4. In a bulkhead structure, the combination of a substantially circular main bulkhead provided with a central opening, reinforcing means therefor comprising compartments disposed around said opening on one face of the bulkhead, a substantially circular flat auxiliary bulkhead of less strength than the main bulkhead providing one wall for each of said compartments, said auxiliary bulkhead having a central opening, an annular bulkhead enclosed by the compartments and aligned with said openings to provide a passageway through the structure, and a closure for said passageway.
5. A bulkhead structure comprising a concavo-convex bulkhead, a flat auxiliary bulkhead, compartments disposed between the bulkheads, a tubular bulkhead enclosed by said compartments and providing a passageway through the structure, and a closure for said passageway.
6. A bulkhead structure comprising a concavo-convex bulkhead, a flat auxiliary bulkhead of less strength than said first named bulkhead, a tubular bulkhead providing a passageway through the structure, compartments disposed around the passageway between the two first named bulkheads, and a closure for said passageway.
7. A bulkhead structure comprising a concavo-convex bulkhead and a pair of flat auxiliary bulkheads, one at each side of said concavo-convex bulkhead.

8. A bulkhead structure comprising a concavo-convex bulkhead, and a pair of flat auxiliary bulkheads, one at each side of said concavo-convex bulkhead and each of less strength than the latter.

9. A bulkhead structure comprising a concavo-convex bulkhead, and reinforcing means for said bulkhead comprising compartments each having one wall provided by the bulkhead and an opposite wall comprised by a flat auxiliary bulkhead.

10. A bulkhead structure comprising a concavo-convex bulkhead, and reinforcing means for said bulkhead comprising compartments at each side of the bulkhead, each compartment having one wall provided by the bulkhead and an opposite wall comprised by a flat auxiliary bulkhead.

11. A bulkhead structure comprising a concavo-convex bulkhead, a pair of flat auxiliary bulkheads one at each side of said concavo-convex bulkhead, and compartments disposed between said bulkheads.

12. A bulkhead structure comprising a concavo-convex bulkhead provided with a passageway, a flat auxiliary bulkhead at one side of said concavo-convex bulkhead and having an opening registering with said passageway, compartments disposed between said bulkheads, and a closure for said passageway.

13. A bulkhead structure comprising a concavo-convex bulkhead provided with a passageway, a flat auxiliary bulkhead contacting the convex side of said first-named bulkhead and having an opening registering with said passageway, compartments disposed between said bulkheads, and a closure for said passageway.

14. A bulkhead structure comprising a concavo-convex bulkhead provided with a passageway, a flat auxiliary bulkhead at the concave side of said first-named bulkhead and having an opening registering with said passageway, compartments disposed between said bulkheads, and a closure for said passageway.

15. A bulkhead structure comprising a concavo-convex bulkhead provided with a passageway, and reinforcing means for said bulkhead consisting of a plurality of compartments disposed around said passageway on each side of the bulkhead, each compartment having one wall provided by said bulkhead and an opposite wall comprised by a flat auxiliary bulkhead, having an opening registering with said passageway, and a closure for the passageway.

In testimony whereof I have signed this specification.

EUGÈNE SCHNEIDER.
